DESCRIPTION

U.S. PATENT DOCUMENTS

FIG. 1 is a front elevational view of a writing instrument with clip ornament embodying my invention;

1,651,437 A * 12/1927 Bochonox ..... 24/102 R
2,320,455 A * 6/1943 Feig ..... 24/11 P
D282,378 S * 1/1986 Ohyabu et al. D19/43
D312,391 S * 11/1990 Vitrac D19/51
D317,625 S * 6/1991 Itoh D19/57

FIG. 2 is a side elevational view thereof;

FIG. 3 is a back elevational view thereof;

FIG. 4 is an alternate side elevational view thereof;

FIG. 5 is top end view thereof;

FIG. 6 is a bottom end view thereof; and,

FIG. 7 is an exploded view thereof.
